UNITED STATES PATENT OFFICE.

FRANK A. RIDER, OF PITTSBURG, PENNSYLVANIA.

AMMONIA-COMPRESSOR.

No. 858,757.

Specification of Letters Patent.

Patented July 2, 1907.

Application filed August 29, 1906. Serial No. 332,514.

To all whom it may concern:

Be it known that I, FRANK A. RIDER, a resident of Pittsburgh, in the county of Allegheny and State of Pennsylvania, have invented certain new and useful

5 Improvements in Ammonia-Compressors; and I do hereby declare the following to be a full, clear, and exact description of the invention, such as will enable others skilled in the art to which it appertains to make and use the same.

10 My invention relates to an improved ammonia compressor, the object of the invention being to provide improvements of this character which will maintain the cylinder cool by the incoming gas, and also provide an improved piston constructed to form a gas cushion preventing pounding and jar to the parts of the piston.

With these and other objects in view, the invention consists in certain novel features of construction and combinations and arrangements of parts as will be 20 more fully hereinafter described and pointed out in the claims:

In the accompanying drawings, Figure 1 is a view in longitudinal section illustrating my improvements, and Fig. 2 is an enlarged view in longitudinal section 25 of the piston.

1 represents the engine bed, which is made with a cylindrical recess or chamber to receive the inner end of the cylinder 2, and provide an annular chamber 3 all around this open inlet end of cylinder 2, for the cold 30 ammonia gas before it enters the open end of the cylinder, keeping that portion of the cylinder as cold as possible to prevent the expansion of the entering gas, which enters the chamber through the inlet 4 located back of the inlet-end of the cylinder to compel the 35 cold gas to completely encircle the cylinder before entering the open end thereof.

A stuffing box 5 is provided at the end of chamber 3, for the piston rod 6, and the chamber 3 also serves as an oil trap to collect oil from the stuffing box and prevent 40 its entrance into cylinder 2, the oil being drawn off through a pipe 7 having a valve 8 therein.

9 represents my improved piston, reciprocated in the cylinder 2, by the rod 6, on which latter, the valve 10 is secured to alternately open and close the end of the piston. The valve 10 and rod 6 are guided in their 45 movement in main piston 9 by a skeleton guide piston 11, which latter is made with an annular recess or groove 12 in its end, and this grooved or recessed end of the guide piston co-operates with an internal flange 13 on the end of main piston 9, to form a gas cushion at 50 14, to prevent jar and shock, as the rod moves back to open the valve 10 and draw the piston 9 backward.

A great many slight changes might be made in the general form and arrangement of the parts described without departing from my invention, and hence, I 55 do not restrict myself to the precise details set forth but consider myself at liberty to make such slight changes and alterations as fairly fall within the spirit and scope of my invention.

Having fully described my invention, what I claim 60 as new and desire to secure by Letters Patent is:—

1. In a compressor, the combination with a cylinder, of a bed provided with a closed chamber constructed to receive the open end of the cylinder and form a gas receiving chamber all around the open end thereof to maintain 65 the cylinder cold and serve as an oil trap, a gas inlet communicating with said chamber, a gas outlet communicating with the cylinder, a stuffing box in the end of the closed chamber, a piston passing through the cylinder, a piston rod in the stuffing box and connected with the piston, and a valved oil outlet in the lower portion of said chamber. 70

2. In a compressor, the combination with a cylinder, of a piston therein, a piston rod, a valve on said rod to open and close a passage through the piston, a skeleton guide piston on the rod movable in the main piston, an internal flange or shoulder on the main piston to limit the movement of the guide piston in the main piston, and said guide piston having a groove or recess in its end co-operating with the internal flange to form a gas cushion. 75 80

In testimony whereof, I have signed this specification in the presence of two subscribing witnesses.

FRANK A. RIDER.
